GROVER C. RUHMAN AND ELO E. PARKER, OF KENEDY, TEXAS.

FUEL ECONOMIZER AND CARBON REDUCER.

Application filed September 19, 1922. Serial No. 589,273.

To all whom it may concern:

Be it known that we, GROVER C. RUHMAN, and ELO E. PARKER, citizens of the United States, residing at Kenedy, in the county of 5 Karnes and State of Texas, have invented new and useful Improvements in Fuel Economizers and Carbon Reducers, of which the following is a specification.

This invention relates to a fuel economizer and carbon reducer or eliminator for use in connection with automobile and other internal combustion motors, one object of the invention being to provide simple, reliable and efficient means, readily applicable to any ordinary type of automobile or other water-cooled internal combustion motor, whereby steam and vapor generated in the radiator may be withdrawn therefrom and separated from any water carried off therewith and such steam and vapor admixed with the fuel charges to secure more complete combustion of the fuel and greater power therefrom, and with a consequent reduction of carbon deposits.

Another object of the invention is to provide a device of the stated character which is simple of construction and adapted to be manufactured and readily installed at a comparatively low cost, which is free from working parts liable to get out of order or cause frequent repairs, and which embodies means for ensuring a thorough separation of water from steam and vapor, the supply of steam and vapor only to the fuel supply system and the positive discharge of the separated water through a preferably located overflow outlet.

A still further object of the invention is to provide a device of the character described which will draw off the steam and vapor from the radiator as fast as formed, thus promoting the cooling action of the radiator to a material degree, which will adapt the motor to run efficiently on low grade fuels, and which will yield greater mileage in the use of the grades of gasoline and like fuels in common use.

With these and other objects in view, the invention consists of the features of construction, combination and arrangement of parts, hereinafter fully described and

claimed, reference being had to the accompanying drawing, in which:

Figure 1 is a sectional elevation of the invention as applied for use in connection with a radiator and intake element of a fuel supply system of an automobile or like motor.

Figure 2 is a horizontal section on the line 2—2 of Figure 1.

Figure 3 is a vertical section on the line 3—3 of Figure 1.

In the illustrated embodiment of our invention, we have shown the device in connection with only such parts of the power system of an automobile or other vehicle as are necessary for its practical disclosure, 1 designating the air intake tube of the carburetor of the motor, and 2 a radiator of any ordinary or preferred construction, said 70 radiator having the usual filling nipple 3 provided with the closure cap 4.

Communicating with the top of the radiator, above the level of the water line thereof, is an overflow pipe 5. This pipe 5 allows 75 the generated steam and the overheated water rising above the normal water level to discharge from the radiator in the usual manner. The pipe 5 extends outwardly at the rear of the radiator and is united by 80 a detachable coupling 6 and an elbow 7 with the water and steam inlet 8 of a T union 9, having a steam and vapor delivery outlet 10 connected with a suction pipe 11. The delivery end of this suction pipe 11 85 projects slightly into the mouth of the air intake tube 1, in spaced relation to the walls thereof, so that under the suction of the engine a partial vacuum will be created in the pipe 11 through the action of the 90 air flowing into the tube 1, without interfering with the air intake action.

The union or coupling head 9 is provided with a third passage or nipple 12 extending downwardly therefrom and arranged intermediate of its ends 8 and 10, which nipple 12 enters the upper or mouth portion of a separator 13. A vertically disposed deflector or baffle plate 14 lies between the inlet and outlet passages 8 and 10 and extends a distance downwardly into the nipple 12. The water and steam overflowing or

drawn from the radiator through the pipe 5 and entering the head 9 through its entrance passage 8 strikes this baffle plate or deflector 14, causing the water and steam 5 to flow downwardly into the nipple 12, and preventing direct passage of the same from the inlet to the outlet 10. The water is thus caused to flow by its greater specific 10 gravity into the separator 13, while the lighter steam and vapor pass around the lower end of the baffle 14 and upwardly on the other side of the baffle and discharge through the outlet 10 into the pipe 11 for delivery to the air intake tube 1. By this 15 means a positive primary separation of the steam and lighter watery vapors will be effected, and provision made for their rapid passage to the fuel supplying system of the engine, while the solid water and the heavier 20 watery vapors flow downwardly into the separator 13 and are prevented from passing to the motor with the steam and lighter watery vapors.

The separator 13 comprises a double 25 frusto-conical chamber formed of an upper conical section 15 and a lower conical section 16 having their bases abutting and united, such cone sections being thus arranged in opposition to each other. Arranged in the 30 upper conical compartment or cone section 15 is a concavo-convex baffle plate 17 having its concaved side facing upwardly and forming a collecting cup, said baffle being provided with a central opening 18. Extending 35 horizontally through the base of section 13 immediately beneath this baffle 17 is a pipe 19. One end or leg 20 of this pipe forms a filling or priming pipe having a water inlet 21 normally closed by a removable plug or other suitable closure 22. The 40 other arm or leg 23 of pipe 19 is coupled at its outer end to a vertical discharge pipe 24. Between the ends or legs 20 and 23 the pipe 19 is provided with a central pipe section 25 extending downwardly into the lower conical section or chamber 16 of the water separator to a point near the lower end thereof. Pipe 24 has a terminal portion 26 which may extend through the base of the radiator 45 2, for the final discharge of the overflow water at the proper point where such water is usually discharged from an ordinary overflow tube.

The pipe 25 forms the short leg, the pipe 55 24 the long leg and the pipe 23 the connection between such legs of a siphon discharge device, through which the water trapped in the chamber 13 will be discharged automatically from said chamber when it reaches the 60 horizontal level therein of the pipe portion 23, while the pipe 20 serves as a water inlet by which water may be supplied to the lower portion of the water trap for the purpose of initially priming the siphon for action and performing this priming action

whenever such becomes necessary. Disposed in the lower cone section 16 of the water chamber or trap is a concavo-convex baffle plate 27 having its convexed face upwardly disposed and provided with an opening 28 70 through which the pipe 25 projects, such opening providing a passage for the down flow of water into the lower portion of said section 16. At its lower constricted end or apex the section 16 is provided with a drain valve or cock 29 which is normally kept closed, but which may be opened whenever desired for the purpose of discharging from the trap any refuse matter or for draining water from the trap for convenience at any 80 time in flushing and cleaning the same or for other purposes.

In the operation of the device, the siphon is first primed by introducing water through the pipe 20 into the bottom section 16 of the 85 water separator until the lower end of the siphon intake leg 25 is submerged, the plug 22 then being applied to seal said pipe 20. When the motor is set into action steam and moisture laden air, at all normal temperatures in the radiator, pass under their pressure and are drawn by the suction induced in the pipe 11 into pipe 5 and pass therefrom into the upper section 15 of the water separator 13, being deflected downwardly 90 thereinto by the baffle plate 14. Any particles of water passing with the steam and vapor will strike the baffle 14 and be caused to trickle down the same into the chamber 13, while the steam and vapor pass around the lower edge of the baffle and into the pipe 11 and from the same into the air intake pipe 1 or other proper part of the fuel supply system. The pipe 5 also receives the normal 105 overflow water in the radiator, when the cooling water is heated and rises to an abnormal extent, this water flowing through the pipe 5 to the separator with the steam and vapor, the steam and vapor discharging through the pipe 11 while the water flows 110 into the upper section 15 of the trap 13, together with the heavier portions of the vapor which may then be drawn by the induced suction through the pipe 11 and pass into the carburetor or intake manifold, the 115 heat of the engine causing this heavier vapor to be vaporized for admixture with the steam and lighter vapor with the fuel charges. The water flowing into the trap or separator 13 strikes the upper concavo-convex baffle plate 120 17, whereby its motion is retarded, and then flows through the opening 18 into the space between the baffle plates 17 and 27 through the opening 28 in the baffle plate 27 into the lower portion of trap section 16 if the latter 125 is not filled. This water contained in the separator or trap, being normally of high temperature, will keep the trap heated and thereby prevent condensation of the steam and vapor. When the water in the trap 130

rises to the level of the cross passage of leg 23 and overflows into the leg 24, a siphonic action will be established which will draw the water from the separator and discharge it through the final outlet or discharge pipe 26.

In practice, while the pipe 11 is shown as arranged for cooperation with the air intake 1 of the carburetor, it may be connected with the fuel intake manifold, the object being to deliver the steam and vapor to the fuel supply system at any suitable point for admixture with the fuel charges supplied to the engine. Also the pipes 5, 15 24 and 26 may be arranged in any convenient manner for the performance of their functions, and if desired the device may be so disposed that the pipe 19 will be disposed above the highest level of the water in the 20 radiator, in which event the pipe 26 may be arranged to return the overflow water to the water chamber instead of discharging it to the atmosphere. It will be observed that great separating efficiency is secured by 25 the construction defined, and that therefore no water can pass with the steam and vapor to the carburetor or intake manifold of the engine. The device may be applied to existing automobiles conveniently by cutting 30 away the ordinary overflow pipe at suitable distances from its upper and lower ends, leaving its upper and lower ends remaining and connecting the pipe 5 to the upper end of the overflow pipe and the pipe 24 to the 35 lower end of the overflow pipe, so that the normal arrangement of the inlet and outlet ends of the overflow pipe will not be disturbed.

The upper baffle plate 17 checks the down flow of water entering the separator from pipe 5, and prevents violent agitation of the water beneath and irregular or premature action of the siphon. The lower baffle plate 27 acts in a similar capacity and prevents 45 violent up and down motion of the water in the lower portion of the separator. The two baffles operating in conjunction prevent the water in the separator from sloshing and from being dashed up into the suction pipe 50 11 under vibrations or tilting motions of the car. A positive and certain action of the separator is thus ensured under all conditions. Withdrawal of the steam and vapor from the radiator as fast as formed is 55 secured through the suction pull in the pipe 11, as well as that occurring through the formation of a partial vacuum in the upper portion of chamber 15. By this means a large percentage of the heat generated in 60 the radiator will be constantly abstracted, keeping the water in the radiator and the motor itself cool, preventing the motor from becoming overheated in the event of derangement of the air fan. We have found 65 that by this rapid extraction of heat the

use of a fan for cooling purposes is not always necessary. It will be observed that the two baffle disks 17 and 27 are in spaced relationship, and that through this relationship an intervening compartment is formed 70 between them, which intermediate compartment is in communication with the upper separating chamber through the opening 18 and with the lower water collection or trap chamber through the opening 28. The disk 75 17 has its concaved face facing upwardly, and therefore all the moisture deposited in the upper separating chamber flows upon this disk and is guided by the sloping surfaces of its convex side toward the opening 80 18 and thence flows into the intermediate chamber. The moisture discharging into the intermediate chamber, if it does not pass immediately through the opening 28 into the trap chamber, is retained in the intermediate 85 chamber and is held therein until its rises to a level above the level of the convex face of the disk 27 and flows over the same to the opening 28. By this means a more or less regular and even flow of the 90 water to the trap chamber is insured and the passing of the water in spasmodic columns or jets to the trap chamber prevented. As a result, the intermediate chamber may 95 serve as an overflow chamber from the trap chamber, in the event of the passage of any considerable body or amount of water to the separator at any time from the radiator, while at the same time the flow of the water in spasmodic jets, such as would be 100 liable to cause irregular or improper action of the siphon, will be effectually prevented and the siphon kept primed at all times for 105 action. This beneficial result, is due, as will be readily understood, to the desired 110 construction and arrangement of the upper, lower and intermediate chambers and baffles. An additional advantage is that the formation of the intermediate chamber permits of the extension of the pipe 20 there- 115 through in such a manner as to avoid interference with the separating action and the discharge of the water by siphonic action from the trap chamber.

We have also found in practice that by 115 the use of this device, which may be readily and conveniently applied to any automobile or other internal combustion motor using a radiator or water cooling device or its equivalent, from which steam and vapor 120 may be extracted or admixed with the fuel charges passing to the engine cylinders, a misty or fog-like vapor is supplied which increases the combustibility of the fuel mixture and hence its power, allowing low grade 125 gasoline to be used with efficiency, and allowing commercial grades to be used with great economy in the way of securing greater mileage on a given percentage of fuel, and with a reduction of carbon deposits. The 130

engine will thus operate with greater power and economy and be kept in much better condition, avoiding the necessity of frequent removal of carbon in the ordinary ways and correspondingly reducing wear and tear on the valves and other working parts.

An important advantage of our device is that it not only ensures the entire separation of the water from the steam and vapor, and prevents condensation of the vapor in the water trap, but ensures the withdrawal from the radiator and supply to the engine of the steam and vapors as fast as produced in the radiator, thus performing the double function of keeping the radiator at a low temperature and supplying the fuel supply system of the motor with a constant stream of vapor to secure greater power and greater working efficiency of the engine and economy in the use of fuel.

Having thus fully described our invention, we claim:—

1. In a vaporizer for internal combustion engines, a water and steam separator comprising a casing having an upper water and vapor receiving chamber and a lower water containing chamber, admission and discharge passages communicating with the inlet of the upper chamber, a baffle plate disposed between said passages and extending downwardly into said inlet, a perforate baffle plate in the upper chamber of the casing, a perforate baffle plate in the lower chamber of the casing, and means for discharging water from said lower chamber.

2. In a vaporizer for internal combustion engines, a water and vapor separator comprising a casing having an upper vapor and water receiving chamber and a lower water receiving chamber, admission and discharge passages communicating with the upper chamber, a concavo-convex baffle disk in the upper chamber provided with a central opening and having its concave side facing upwardly, a concavo-convex baffle disk in the lower chamber provided with a central opening therein and having its concave side facing downwardly, and means for discharging water from the lower chamber.

3. In a vaporizing device for internal combustion engines, a water and vapor separator having an upper water and vapor receiving chamber and a lower water receiving chamber, admission and discharge passages communicating with the upper chamber, perforate baffle plates in said chambers, and a priming and siphon discharge device comprising a horizontal pipe extending through the casing between said baffle plates and having its opposite end portions forming a priming pipe and the central portion of a siphon tube, respectively, said priming pipe being provided with an inlet and a closure therefor, an intake siphon leg depending from said horizontal pipe through

the perforation in the lower baffle plate into the lower portion of the lower chamber, and a long siphon leg communicating with the outer end of the intermediate siphon portion of the horizontal pipe.

70

4. In a vaporizing device for internal combustion engines, a water and steam separator comprising a casing having an upper frusto-conical chamber and a lower frusto-conical chamber, said chambers being arranged in opposition, a connection at the upper end of the upper chamber provided with admission and discharge passages, a baffle between said passages, a concavo-convex centrally perforated baffle plate in the upper chamber having its concave side facing upwardly, a centrally perforated concavo-convex baffle plate in the lower chamber having its convex side facing upwardly, and a siphon discharge device including an outer leg portion, an intermediate portion communicating with the casing between said baffle plates, and an inner leg portion extending therefrom downwardly through the perforation in the lower baffle plate to the portion of the lower casing therebelow.

80

5. In a vaporizer for internal combustion engines, a water and steam separator having an upper separating chamber, a lower article collection chamber, and an inlet with admission and discharge passages communicating with said separating chamber, a baffle plate disposed between said passages and leading into the inlet, baffles in said separator between said chambers for preventing vertical movement of bodies of water therein, and means for periodically draining the water from said collection chamber.

90

6. In a vaporizing device for internal combustion motors, the combination of a separator having an upper frusto-conical portion and a lower frusto-conical portion, a connection at the upper end of the upper frusto-conical portion provided with admission and discharge passages, a baffle disposed between said passages, a perforate baffle plate in the upper frusto-conical portion of the separator, a perforate baffle plate in the lower frusto-conical portion of the separator, and a siphon discharge device having its intake leg communicating with the lower frusto-conical portion of the separator below the baffle therein.

100

7. In a vaporizing device for internal combustion motors, a separator comprising an upper frusto-conical portion and a lower frusto-conical portion, a connection at the upper end of the upper frusto-conical portion provided with admission and discharge passages, a partition or deflector between said passages, a perforate baffle plate in the upper frusto-conical portion of the separator, a perforate baffle plate in the lower frusto-conical portion of the separator, and a siphon discharge device including a pipe

110

115

120

125

130

passing through the chamber between said baffles and having a limb extending through the lower partition into the lower compartment of the separator, one end of said pipe forming a filling connection having a detachable closure, the other end of said pipe forming a cross portion between the siphon

legs, and a discharge leg connected with the said end of the pipe.

In testimony whereof we affix our signatures.
